UNITED STATES PATENT OFFICE.

EDWARD L. WATROUS, OF DES MOINES, IOWA, ASSIGNOR TO DAVID B. GANN, OF CHICAGO, ILLINOIS.

COMBINED LATCH AND HANDLE.

1,086,571.

Specification of Letters Patent. Patented Feb. 10, 1914.

Application filed March 20, 1909. Serial No. 484,658.

To all whom it may concern:

Be it known that I, EDWARD L. WATROUS, a citizen of the United States, residing at Des Moines, in the county of Polk and State of Iowa, have invented a new and useful Combined Latch and Handle, of which the following is a specification.

The object of my invention is to provide a latch of simple, durable and inexpensive construction, that may be formed complete of sheet metal, and made with dies and formers, and without hand work.

More specifically it is my object to provide a device of this kind especially adapted for use in connection with the hinged covers of washing machines and the like, for the purpose of firmly and securely holding the cover in its closed position, and also for the purpose of providing a convenient handle 20 by which the cover may be elevated.

A further object is to provide a combined latch and handle by which the washing machine or other device to which the latch is attached, may be carried.

My invention consists in the construction, arrangement and combination of the various parts of the device, whereby the objects contemplated are attained, as hereinafter more fully set forth, pointed out in my claims and illustrated in the accompanying drawings, in which—

Figure 1 shows a front elevation of the combined latch and handle embodying my invention, and applied to a part of a washing machine. Fig. 2 shows a top or plan view of same. Fig. 3 shows a sectional view through the upper portion of the latch and handle on the line 3—3 of Fig. 2. Fig. 4 shows a sectional view on the line 4—4 of Fig. 1. Fig. 5 shows a front elevation illustrating a modified form of my invention, and Fig. 6 shows a sectional view on the line 6—6 of Fig. 5.

Referring to the accompanying drawings, I have used the reference numeral 10 to indicate the upright portion or body of a washing machine, or other device to which my improved latch and handle is applied, and 11 indicates the hinged cover thereof.

The upper portion of the latch comprises a sheet metal plate 12 designed to be connected with the cover 11 by means of screws 13 in its end portions. Near the central portion of the plate 12 I have formed a transverse rib 14 designed to receive the ends of

a wire handle 15, and to hold said ends between the under surface of the rib, and the top surface of the cover 11. Adjacent to the transverse rib 14 is a transverse raised portion 16, materially shorter in length than the rib 14, for the purpose of providing a hinge point, as will hereinafter appear.

The hinged member of the latch is formed complete of a single piece of sheet metal, and comprises an upper end portion 17 having its end formed into a cylinder 18, which cylinder is inserted under the raised portion 16, to thereby form a pivotal connection between the plate 12 and the part 17. Below the part 17, the hinged member is curved outwardly and downwardly at 19 and its lower end portion is provided with a slot 20. Below the slot, it is extended outwardly at 21, as shown in Fig. 6, and then downwardly and outwardly, to form a handle 22.

The part of the latch that is connected to the body 10 comprises a plate 23 made of a single piece of sheet metal and connected with the body portion by means of screws. The plate 23 is formed of a blank which is provided near its upper end with lateral wing portions of uniform size and shape, and a central vertical slot in line therewith. These wing portions are folded back against the body of the plate, and their ends are inserted through the slot, thereby forming a projection 24 for engagement by the hasp or hinge member 19.

At the lower end of the plate 23 is a transverse raised portion 25, designed to receive the ends of a wire handle 26. Pivotally connected to the plate 23 below the projection 24, is a clamping lever made of a single piece of sheet metal and connected by a pivot pin 27 with the part 23. This lever has a curved extension 28 so arranged that when the handle 29 is elevated, the curved extension 28 will project upwardly at one side of the projection 24, so that the lower end of the hinged member 19 may move to position with its slot 20 surrounding the projection 24, then after it is in its position, the handle 29 may be lowered to thereby cause the extension 28 on the lever to engage the part 21, and force it downwardly and thereby securely lock the parts of the latch together. In order to limit the movement of the lever, I have provided a lug 30 on the part 23.

In the modified form shown in Figs. 5 and 6, the handle 26 is omitted from the lower end of the part 23, and hence the latch may be constructed somewhat cheaper than 5 the form shown in which this handle is present.

In the construction of my improved latch, it is obvious that all of the parts may be made of sheet metal and wire, and may be 10 cut out and shaped by dies and formers, without any hand work.

In practical use, it is obvious that when the latch is in its closed position, the cover 11 will be firmly held to its closed position 15 by the engagement of the extension 28 with the part 21. Furthermore, all side movement of the cover will be prevented by means of the projection 24 in the slot 20. When it is desired to release the latch, the 20 operator elevates the handle 29 on the lever, and then grasps the handle 22 and moves it outwardly away from the extension 24. Then he may grasp the handle 15 that is attached to the cover, and thereby raise the 25 cover. The handle 26 may be used for the purpose of grasping and carrying the washing machine or other device to which the latch is attached.

I claim as my invention:

30 1. A latch device of the class described, comprising a hinged member of sheet metal having a downwardly extending portion provided with a slot, the lower end of said hinged member being extended outwardly to 35 form a cam engaging portion and down-

wardly to form a handle, a sheet metal plate having a rigid lug adapted to enter said slot, and a lever pivoted at an intermediate point to said plate, said lever having at one side of the pivot a handle and at the other 40 side a curved extension designed to be rotated into cam engagement with the outwardly extending portion at the lower end of said hinged member.

2. A latch device of the class described, 45 comprising a hinged member of sheet metal provided with a locking portion and a slot, a sheet metal plate rigidly supported in operative relation to said latch member, a resilient locking member pivoted to said plate 50 at a point below said hinged latch member, said locking member being arranged to swing under the end of said latch member and being provided with a cam surface adapted to ride over said locking portion, 55 whereby said members are locked together, and a lug on said plate arranged to enter said slot.

3. A latch device of the class described comprising, in combination, an apertured 60 hasp, and a base plate of sheet metal having a hasp-engaging lug formed of a pair of lateral wings bent backwardly and forwardly through an opening in the plate.

Des Moines, Iowa, December 12, 1908.

EDWARD L. WATROUS.
